UNITED STATES PATENT OFFICE.

FERDINAND WESEL, OF NEW YORK, N. Y.

PRINTER'S PROOF-PRESS.

SPECIFICATION forming part of Letters Patent No. 608,813, dated August 9, 1898.

Application filed December 27, 1895. Serial No. 573,456. (No model.)

To all whom it may concern:

Be it known that I, FERDINAND WESEL, a citizen of the United States, residing at New York, (Brooklyn,) in the county of Kings and State of New York, have invented certain new and useful Improvements in Printers' Proof-Presses, of which the following is a specification.

This invention relates to that class of printing-presses known as "proof-presses," which are used in newspaper and other offices for taking proofs from forms of various widths, said press being arranged for feeding several independent webs of paper of a width corresponding to the forms set up; and the invention relates more especially to certain improvements in the printer's proof-press for which Letters Patent were granted to me heretofore, No. 537,658, dated April 16, 1895, whereby the press is better adapted for newspaper-work, as it enables the simultaneous proof-taking of several forms of different widths and sizes and the feeding of independent webs of paper to the same, the ends of said webs being held by a suitable gripping device above the forms while the impression-roller is moved back over the forms and released again when the impression-roller is moved forward over the forms for taking proof.

The invention consists of a proof-press for newspaper and other printing offices which comprises a feed mechanism by which the ends of the webs of paper are fed for a short distance after the proof-printed sheet is torn off, a gripping device for holding the ends of said webs in position without interfering with the form during the backward motion of the impression-roller, and of means by which the gripping mechanism is released when the impression-roller is moved in forward direction for taking proof.

The invention consists, further, of a printer's proof-press in which the shaft of the paper-feeding rolls is provided with fixed and with adjustable and independently-movable core-pieces and an independent sleeve or sleeves also provided with fixed and adjustable core-pieces for supplying several webs of paper of varying width to the forms, as will be fully described hereinafter and finally pointed out in the claims.

In the accompanying drawings, Figure 1 represents a side elevation of my improved printer's proof-press, in which the carriage is shown as having reached the end of its forward movement, while the sliding cams are shown as shifted. Fig. 2 is a plan view of the same, partly in horizontal section, on line 2 2, Fig. 1. Fig. 3 is a detail perspective view of the mechanism for holding, gripping, and releasing the web or webs of paper for taking proof, drawn on a larger scale. Fig. 3^a is a sectional view of the gripping mechanism corresponding to the position of the parts in Fig. 3. Figs. 4 and 4^a and 5 and 5^a show, respectively, detail side views and vertical sections of the gripping mechanism in its successive positions; and Figs. 6, 7, and 8 are respectively a detail plan view, a vertical longitudinal section, and a vertical transverse section on line 8 8, Fig. 7, of the roll-supporting shaft with two different cores for the paper-rolls.

Similar letters of reference indicate corresponding parts.

Referring to the drawings, A represents the supporting-frame of my improved proof-press for newspaper and other printing offices. The supporting-frame is composed of upright standards *a a*, which are braced by longitudinal and transverse tie-rods. On the standards is supported a bed-plate B, which is provided at each side with guide-rails *b b*, on which a reciprocating carriage C is guided. Motion is imparted to the reciprocating carriage C by means of a transverse shaft D, having a crank-handle D', which shaft carries an impression-roller F, to each end of which are applied gear-wheels *d*, that mesh with fixed racks *d'*, supported at both sides of the bed-plate B. By turning the crank D' in one or the other direction the carriage C is moved forward or backward over the bed-plate B. At one end of the carriage C, supported in inclined bearings *e*, are two inking-rollers E E, which are in contact with an ink-transferring roller E', the shaft of which turns in bearings of the frame of the carriage. The roller E' receives ink by means of intermediate rollers *e' e'* from a suitable ink-fountain E², that is arranged above the intermediate rollers, as shown in Fig. 1. A transverse shaft G' is supported in bearings at the up-

- per ends of upright standards G at one end of the frame of the carriage C, said shaft carrying a plurality of rolls of paper, which move with the carriage C over the bed-plate B.
- 5 The webs of paper pass from the rolls over suitable rollers g g' , of which roller g is a mere guide-roller, while roller g' is a friction or pressure roller, said rollers being supported in the slotted arm of an oscillating frame g^2 ,
- 10 the pivot-shaft of which extends from one side of the frame of the carriage to the other. The supporting-frame g^2 of the rollers g g' is provided with forwardly-extending arms g^3 on both sides, said arms carrying antifriction-rollers g^4 , which move over the guide-rails b and over auxiliary rails r at both sides of the bed-plate and which serve for the purpose of oscillating the frame g^2 when passing onto the rails r , so as to move the friction-roller g'
- 15 into contact with the impression-cylinder F for the purpose of drawing the webs of paper in the opposite direction to the motion of the carriage when the carriage is arriving at the end of its forward motion. This feature is
- 20 shown in my previous patent referred to, but its function and operation will be more fully described in detail hereinafter. At the opposite side of the impression-cylinder F the frame of the carriage is provided with a bend-
- 25 ing and cutting device I, which is composed of a cutting-blade i , that is sharpened at its lower edge and attached at its upper edge to a transverse bar i' , that is pivoted to the carriage C. A bending-bar i^2 is attached to the
- 30 knife-blade i and extended below the sharpened edge of the same, the lower end of said bending-bar being rounded off, so as to press the paper into a groove i^5 on the raised end portion of the bed-plate, as shown in Fig.
- 35 3^a. To the transverse bar i' is also attached an arm or finger i^3 , by which the motion of the cutting-blade and bending-bar in one direction is produced. To one end of the transverse bar i' is attached one end of a helical spring i^4 , the other end of which is attached to a fixed point on the carriage, so that when it is not set to tension the spring will hold the cutting-blade and the bending-bar in inclined position adjacent to the impres-
- 40 sion-roller F, as shown in Fig. 5^a. When the carriage C arrives at the end of its forward motion, the finger i^3 abuts against the raised end portion of the bed-plate and moves thereby the cutting-blade and the bending-bar against
- 45 the tension of the spring i^4 into vertical position, as shown in Fig. 3^a, so that the bending-bar clamps the web or webs of paper firmly into the groove i^5 in the bed-plate, while the cutting-blade permits the tearing off by the
- 50 attendant of the proof taken during the forward motion of the carriage. As soon as the carriage commences its return motion the contact of the finger i^3 with the end portion of the bed-plate is discontinued and the cutting-
- 55 blade and bending-bar are returned again by the action of the spring i^4 into their former inclined position, as shown in Fig. 5^a.

The carriage C is provided at its opposite sides with sliding cams L, which are provided at their under side, below the shaft of the impression-cylinder, with inclined cleats l, that are retained in position by suitable set-screws l'. On the upper side of the sliding cams L are arranged inclined upwardly-extending lugs l². The cleats l rest on eccentrics l³, which are mounted on the vertically-movable standards C' of the carriage, and can be raised or lowered by suitable handles, as is shown in my said patent, especially in Fig. 6^a thereof. The sliding cams L are guided on the eccentrics l³ and on suitable lugs l⁴ on the frame of the carriage and are operated in connection with stops s s' on the bed-plate of the carriage, the stops s at left end of the bed-plate being arranged in longitudinal slots 85 s² of the guide-rails b b, whereby they can be adjusted and the motion of the carriage C limited as required by the length of the proofs to be taken. The shaft of the impression-cylinder is journaled in bearings of upright standards C', which are guided in vertical ways of the carriage C and engaged at their lower ends by the free ends of springs l⁵, which are applied at their opposite ends to the lower part of the carriage C, as shown in 95 Fig. 1, the tension of said springs tending to press the standards C' in upward direction and the eccentrics l³ against the cleats l of the sliding cams L. The tension of the springs l⁵ can be adjusted by tension-screws l', turning in lugs of the carriage C.

The carriage C is provided with antifriction-rollers C², that rest on the sliding cams L and facilitate the shifting of the same when they arrive in contact with either stop s or s', 105 the journals of said rollers passing through slots in said standard, as in my patent referred to. These rollers C² also retain the sliding cams in position against upward displacement, so that said sliding cams may force the eccentrics l³ and the impression-cylinder F in downward direction against the motion of the springs l⁵ and into position for printing. The short auxiliary rails r, arranged at one end of the rails b, are beveled at their inner ends 115 and guided on stationary headed pins r². The said rails r carry upwardly-projecting pins r³, which are each adapted to be engaged on one side by a projection r⁴ on the carriage C and on the other side by the beveled nose r⁵ 120 on the end of the spring-finger r⁶. The beveled ends of the rails r permit the rollers g⁴ of the frame g² to pass freely onto the rails r when the carriage C is near the end of its forward motion, whereby the frame g² is oscillated and the friction-roller g' of the same brought in contact with the impression-roller F, as shown in Fig. 3^a. As soon as the impression-roller leaves the form the printed proof would be drawn over the form or else 130 torn unless the friction-roller g' is brought against the impression-roller F. Thereby an additional length of paper is fed, corresponding to the distance between the end of the

form and the extreme limit of forward motion, due to the fact that the friction-roller g' is positively driven by reason of its pressing the paper web against the impression-roller.

5 During the backward motion the paper must be fed in the opposite direction until the end of the web is about to be released by the clamp i^2 and blade i . Otherwise an objectionable loop would be formed under the impression-cylinder. This feed of the web is secured by keeping the roller g' in contact with the impression-cylinder a short time after the return of the carriage is commenced, which operation is accomplished as follows:

15 When the carriage is nearing the end of its forward movement and the rollers g^4 rise up on the ends of the auxiliary rails r , the pins r^3 are engaged by the projections r^4 on the carriage, which causes the rails to be pushed forward, with the said rollers still on the end of the rails, until the forward movement of the carriage is completed. By this construction the rollers g^4 are permitted to leave the rails r very soon after the return movement

25 is commenced. After the rollers g^4 leave the rails r the inner sides of the noses r^5 engage pins r^3 and move the rails back to their former position. The inner sides of the noses r^5 are beveled to such an extent as that they can

30 act on the pins r^3 to move the rails back; but they do not prevent their snapping over and past the pins as the carriage is being moved back. On the other hand, the outer sides of the noses are so much beveled as that during

35 the forward movement of the carriage they slip over and past the pins without acting on the rails. As the extra length of paper below the impression-roller would be in the way of the same during the return motion of the carriage, it is necessary to retain each web of paper by the gripping device, which device is formed by the cutting-blade i and a bent gripping-finger m . (Shown in Fig. 3.) The gripping device holds the end of each web of paper in raised position above the form or forms, so as to permit the return of the carriage over the form without any tearing or rumpling up of the paper. In order that the gripper may clamp the end of

40 the web onto the blade i , as hereinafter described, it is necessary that the end of the web be projected a short distance past the edge of the blade. This is accomplished by releasing the roller g' slightly before the end of the web is released by the blade, whereby a slight loop is formed under the impression-roller, which loop straightens out, due to the stiffness of the paper, and the end of the web

45 springs past the edge of the blade when released thereby. When the carriage arrives at the end of its backward motion, the gripping device is released and the paper fed during the forward motion of the carriage to the impression-roller and forms. As soon as the

55 impression-roller arrives over the form during its forward motion the paper is held thereby down upon the form and an impression

taken. The paper being thus held between the impression-roller and the form, the same is fed automatically to the latter as the carriage moves along. When the carriage arrives at the end of its forward motion, as shown in Fig. 1, the impression-roller F is lifted by the shifting of the sliding cams L , caused by their contact with the end stops s' , 70 the shifting motion bringing the cleats l over the eccentrics b^3 . Simultaneously the journal-bearings of the inking-rollers E ride up on the inclined lugs of the sliding cams L , so that the rollers E are thereby bodily lifted 75 over the form. The impression-roller and the inking-rollers being thus lifted are then moved with the carriage in backward direction over the form without coming in contact therewith until the carriage arrives at the 80 opposite end of the bed-plate, when the opposite ends of the sliding cams L form contact with the stops s at that end, so as to shift the sliding cams L and move the cleats l back over the eccentrics b^3 , whereby the impression-roller as well as the inking-rollers are 85 returned into their former lower position and are then moved by the forward motion of the carriage over the forms. During the forward motion of the carriage the inking-rollers pass over the form ahead of the impression-rollers and supply the ink required for printing the proofs, while the impression-roller rolls the paper, so to say, over the forms and produces the unwinding of a sufficient 90 length of paper for taking the proofs.

As it is necessary in newspaper offices to take proofs from forms of various widths which are supported on the bed-plate, it is necessary to arrange a plurality of webs of paper on the shaft G' , said shaft being provided with one or more fixed cores G^2 and with one or more adjustable cores G' , so as to provide for the exact width of each web to be used. The cores G^2 G^3 of one of the rolls of paper are attached directly to shaft G^2 , so that the same turns with the paper while it is fed to the impression-roller in taking proof. The cores G^2 G^3 of the other rolls are applied to independent sleeves G^4 , placed loosely on the shaft G' , so that these rolls can turn independently of the shaft G' and supply the webs to the impression-roller and forms when taking proofs of additional forms placed on the bed-plate. The arrangement of an independent sleeve G^4 on the shaft G' is clearly shown in Figs. 7 and 8 and forms one of the features by which my improved proof-press is better adapted for newspaper offices than the press heretofore patented by me.

It is obvious that a gripping device has to be arranged for each web separately. The gripping devices are shown in plan view in Fig. 2 and in their different successive positions in Figs. 3, 3^a, 4, 4^a, 5, and 5^a. They are applied to a cranked transverse shaft t , which is supported on the standards G of the carriage C back of the impression-roller F . To the outer end of the cranked shaft t is keyed

a short arm t' and adjacent and approximately at right angles thereto a cam t^2 , as shown in Fig. 3. A helical spring t^3 is attached at one end to the shaft t and at the other end to the standard G , said spring exerting a motion in downward direction on the cranked portion of the shaft t . Below the arm t' and in contact therewith is arranged a slide-piece t^4 , which is guided in ways of a bracket t^5 , attached to the standard G . The lower end of the slide-piece t^4 rests on the concaved wider portion t^6 of an elbow-piece t^6 , the upper end of which is keyed to the outer end of the bar i' . Adjacent to the elbow-piece t^6 is loosely applied to the bar i' a lever t^8 , which is located in the plane of the cam t^2 and concaved at its upper end. The lower end of the lever t^8 is slotted and connected with a fixed pin t^9 on the inner end of the sliding cam L , as shown in Fig. 3. The parts described—namely, the arm t' , the cam t^2 , the slide-piece t^4 , the elbow-piece t^6 , and the lever t^8 —serve, in connection with the shaft t , bar i' , and the sliding cam L , to impart the required motion to the gripping devices, so as to set them into the required positions for gripping and releasing the ends of the webs at the proper time.

When the carriage arrives at the end of its forward motion, the sliding cams L are shifted and the impression-roller and inking-rollers raised, as before described. Simultaneously therewith the arm i^3 abuts against the end portion of the bed-plate and moves the cutting-blade and bending-bar down, so as to press the web firmly on the bed-plate, as shown in Figs. 3 and 6. The proof-printed portion of the web is then torn off along the cutting-blade by the operator. When the impression-cylinder leaves the type, the frame of the friction-roller g' is oscillated by the rollers g^4 moving over the rails r , and the said roller g' is placed in contact with the impression-roller. The contact of the arm i^3 with the bed-plate imparts an axial turning motion to the bar i' and a lifting motion to the elbow-piece t^6 , which latter raises the slide-piece t^4 , the latter again lifting the arm t' and turning the cranked shaft t against the tension of its spring t^3 , as shown in Fig. 3. The gripping-finger m on the shaft is thereby likewise raised, so that the proof-printed web can be torn off without being interfered with by the finger m . The shifting motion of the sliding cam L moves the upper end of the oscillating lever t^8 away from the cam t^2 , as shown in Fig. 3. The operator then turns the crank D' so as to move the carriage in backward direction over the form. On the return motion of the carriage the finger i^3 is released and the bar i' , with the cutting-blade and bending-bar, returned by its spring i^4 into its normal position. (Shown in Fig. 4^a.) The elbow t^6 is moved in downward direction with the bar i' , which motion is immediately followed by the slide-piece t^4 , arm t' , and shaft t , which are under the influence of the spring t^3 , so as to place the parts into the position

shown in Fig. 4. Simultaneously therewith the lower end of the web is moved out, as before described, for a short distance beyond the edge of the cutting-blade in the manner previously described. The gripping-finger m , being moved in downward direction by the turning of the shaft t , takes up the end of the web and presses it against the edge of the cutting-blade, so as to firmly grip the same, as shown in Fig. 4^a, and holds it thus gripped until the carriage arrives at the end of its backward motion. The sliding cams L , being shifted by the stop s at the opposite end of the bed-plate, produce the lowering of the impression-roller and inking-rollers, as before described, and simultaneously therewith the oscillation of the lever t^8 , and thereby by the action of its upper end on the cam t^2 the turning of the shaft t against the tension of its spring t^3 , the lifting of the gripping-finger m , and the releasing of the web, as shown in Figs. 5 and 5^a. The operator then reverses the motion of the crank D' and moves the carriage forward over the form, so as to take the next proof, as before described. When the carriage arrives at the end of the bed-plate, the shifting of the sliding cams by their contact with the stops s' takes place again, also the pressing down of the webs on the raised end portion of the bed-plate, so that the proof-printed webs can be torn off. The backward motion next imparted to the carriage again produces the feeding of a short length of the web beyond the cutting-blade and the gripping of the web by the latter and the descending gripping-finger, as before described.

By placing several forms on the bed-plate and arranging a corresponding number of rolls of paper on the shaft G' several proofs can be taken at the same time, the widths of the rolls corresponding to the widths of the forms, while all the webs are simultaneously gripped during the return motion of the carriage, so as not to interfere in the least with the forms during the return motion of the impression-roller over the same, and released at the beginning of the forward motion, so as not to interfere with the proper printing of the proofs by the press.

Having thus described my invention, I claim as new and desire to secure by Letters Patent—

1. In a printer's proof-press, the combination of a reciprocating carriage, sliding cams arranged at the sides of said carriage, means for shifting said sliding cams when the carriage arrives at either end of its motion, and a gripping device adapted to grip and retain the end of the paper during the return motion and release it during the forward motion of the carriage, substantially as set forth.

2. In a printer's proof-press, the combination of a reciprocating carriage, sliding cams at the sides of said carriage, means for shifting said sliding cams when the carriage arrives at either end of its motion, means for gripping the end of the web so as to retain the

same during the return motion of the carriage, and means for releasing the gripping device from the web when the carriage arrives at the end of its return motion, substantially as set forth.

3. In a printer's proof-press, the combination of a reciprocating carriage, sliding cams arranged at the sides of the carriage, means for shifting said sliding cams when the carriage arrives at either end of its motion, a spring-actuated and oscillating cutting-blade, spring-actuated gripping-fingers applied to a spring-actuated shaft, and means for operating the gripping-fingers so as to grip and retain the web of paper during the return motion and release it during the forward motion of the carriage, substantially as set forth.

4. In a printer's proof-press, the combination of a reciprocating carriage moving over said bed-plate, sliding cams arranged on the sides of the carriage, means for shifting said sliding cams when arriving at either end of its motion, a spring-actuated bar, a cutting-blade applied to said bar, a spring-actuated shaft, gripping-fingers applied to said shaft, an elbow-piece on the bar of the cutting-blade, a short arm and a cam on the shaft of the

gripping-fingers, a slide-piece between the elbow-piece and the arm on said shaft, and an oscillating lever fulcrumed to the bar of the cutting-blade and connected at the lower end with one of the sliding cams, its upper end being adapted to engage the cam on the shaft of the gripping-fingers so that the said fingers, in connection with the cutting-blade, grip or release the web of paper, substantially as set forth.

5. In a printer's proof-press, the combination, with paper feeding and printing mechanisms, of a supporting-shaft for the rolls of paper, provided with a fixed core and an adjustable core, and an independent sleeve on said shaft, also provided with a fixed core and an adjustable core, so as to support several rolls of paper of various widths, on the same shaft, substantially as set forth.

In testimony that I claim the foregoing as my invention I have signed my name in presence of two subscribing witnesses.

FERDINAND WESEL.

Witnesses.
